COMBINED PERFUME BOTTLE AND STAND OR SIMILAR ARTICLE

Eric de Kolb, New York, N. Y., assignor to Coty, Inc.,
New York, N. Y., a corporation of Delaware

Application March 4, 1957, Serial No. 45,055

Term of patent 14 years

(Cl. D86—10)

Fig. 1.

Fig. 2.

Fig. 3.

Fig. 4.

Fig. 1 is a front elevational view of a combined perfume bottle and stand or similar article, showing my new design;

The dominant features of my design reside in the portions shown in full lines.

I claim:

The ornamental design for a combined perfume bottle and stand or similar article, substantially as shown and described.
